UNITED STATES PATENT OFFICE.

WILLIAM BALLARD, OF NEW YORK, N. Y.

BENT TIMBERS FOR SHIPS' FRAMES.

Specification of Letters Patent No. 11,007, dated June 6, 1854.

To all whom it may concern:

Be it known that I, WILLIAM BALLARD, of the city, county, and State of New York, have invented a new and Improved Mode of 5 Shaping and Framing Ships' Timbers; and I do hereby declare the following to be a full description of the same.

The nature of my invention consists in making the framing timbers known as "floor 10 timber," "naval timber," "1st futtock timber," "2nd futtock timber," "top timber and half top timber" from one stick of timber, by bending the same by any suitable means, to the shape required; in combination with 15 the timber so bent, (at the point known as the "naval timber") of a plate of iron so as to be concealed in the wood and protected from the action of the bilge water and atmosphere; also in removing the heart of the 20 wood, by splitting the stick of timber, when bent, so as to prevent rot in the timber, the two halves being joined together again by bolts, so as to leave space enough between the halves to admit of a free circulation of 25 air. But to describe my invention more particularly I will refer to the accompanying drawings forming a part of this schedule, the same letters of reference wherever they occur referring to the same parts.

30 Figure 1, is a side elevation of one of the framing timbers of a ship, showing the whole of the flooring of a ship. Fig. 2, is a vertical inside view of the framing timber as taken from the line α , α , Fig. 1. Fig. 35. 3, is a perspective view of a framing timber as composed of the floor timbers, naval timber, 1st and 2nd futtock timbers, top and half top timbers.

40 Letter A is a representation of the framing timber, as bent from a single stick of timber. At the upper ends of the timber it is flattened down so as to be about half as thick as the lower end.

45 Letter B, is a plate of iron let into the timber at the point known as the naval timber. This plate of iron is let into the timber

after it is bent, and being a stiff, heavy piece of metal, acts as a support or brace to strengthen the timber. At the point C, the half floor timber is joined to the naval timber or point known as the naval timber. This flooring timber D, is an independent piece of timber to which the opposite framing timbers are attached, or bolted, and joining on to the keel, and held down by the 50 keelson. When the stick of timber is bent to the proper shape, it is then split down by the saw and the heart removed, and is then put together again, or nearly so, pins or wedges 55 e , e , e , being inserted between them so as to allow of the passage of air between the halves of the timbers. The halves are then bolted together by the usual methods well known to shipwrights.

In Fig. 3, the various pieces of timber 60 used in the ordinary process of framing ship timbers are marked by their respective names, so as to illustrate more fully the importance of the invention, not only on account of the great difficulty in getting "natural crooks" for naval timbers, but also on account of the greater strength obtained in the timbers, and at the same time greater facility in handling and putting up the 65 frame of a ship.

70 Having described my invention I will proceed to state what I claim and desire to secure, by Letters Patent of the United States—

Cutting the heart out of artificially bent 75 ship timbers, at the curve or bend known as the naval timber, and combining therewith an iron plate (curved so as to fit the curve of the timber), by inserting it in the place cut out of the timber, so as to be protected 80 from rusting by the action of the atmosphere or bilge water of the ship, substantially as hereinbefore described.

85 WILLIAM BALLARD.

Witnesses present:

CHARLES L. BARRITT,
JOHN B. DEMITT.
